INVENTOR
Edward B. Winters.
BY Arthur L. Brown
ATTORNEY

UNITED STATES PATENT OFFICE.

EDWARD B. WINTERS, OF COFFEYVILLE, KANSAS.

STROKE-MULTIPLYING PARALLEL-MOTION DEVICE.

Application filed May 29, 1924. Serial No. 716,808.

To all whom it may concern:

Be it known that I, EDWARD B. WINTERS, a citizen of the United States, residing at Coffeyville, in the county of Montgomery 5 and State of Kansas, have invented certain new and useful Improvements in Stroke-Multiplying Parallel-Motion Devices; and I do declare the following to be a full, clear, and exact description of the invention, such 10 as will enable others skilled in the art to which it appertains to make and use the same, reference being had to the accompanying drawings, and to the figures of reference marked thereon, which form a part of this 15 specification.

This invention relates to a stroke multiplying device designed for providing a relatively long stroke to a reciprocating member to be actuated and the invention comprehends the provision of means for providing what is commonly known as a parallel motion so that the reciprocating movement will be maintained in a substantially straight line, this being important in certain arts, as 25 for example in pumping oil wells.

The invention is illustrated as applied to an oil well rig but in its generic aspect it is capable of other uses such as a pumping jack or wherever a relatively long stroke reciprocating motion is to be provided. I therefore do not wish to be limited entirely to the use of the device in connection with the oil well industry. Such a device is important however in the oil well industry because the pump rods usually receive their motion from the walking beam of the drill rig. In view of the fact that the walking beam receives its motion from the crank on the band wheel and in view of the fact that 30 a relatively short crank is used in drilling, it will be apparent that the reciprocations of the drill rods are relatively short, therefore in order to obtain production, the pumping apparatus must be operated at a 35 relatively rapid rate. When this is done, the rods buckle and crystallize so that they part, necessitating shut downs while repairs are being made. In fact this is such a common practice that it is not unusual for the 40 rods to part once every 24 hours, with a consequent result of loss in production during the time that repairs are being made.

With my invention, the pump rods may be operated so as to provide a stroke for the 45 pump piston of from sixty inches to one-hundred twenty inches, at from 8 to 16

strokes per minute, as against the present practice where the stroke of the pump piston is from 14 to 36 inches and operated from 20 to 40 strokes per minute. Therefore it will be seen that with the old style practice the whipping of the rods must ensue whereas with the long slow motion, not only will increased production be provided, but the tendency for the rods to whip and crystallize will be reduced to a minimum. 60

Long stroke pumping mechanisms are of comparatively recent origin, their necessity being due largely to the fact that deeper wells are being drilled and to the fact that 70 many oil producing wells have considerable water and unless a greater amount of fluid is pumped from the well, the oil recovered will not pay for operating the well. It is not my intention to represent that with my invention the liability of the rods parting will be wholly eliminated because I believe that it will be impractical to entirely eliminate the parting of the rods but I do claim that with my invention the parting of the 75 rods will be considerably less frequent than with the standard pumping outfit. I have therefore provided means whereby the power delivering means to be connected to the pump rods can be swung out of the way 80 of the pump rods when it is necessary to pull them and I have provided the parallel motion so that there will be direct straight pull on the pump rods which will give greater economy in power consumption than 85 mechanisms where the pull deviates materially from a straight line and by maintaining the pump rods substantially in the center of the well, liability of their slapping against the tubing will be entirely eliminated. 90

The novelty of the invention as well as its practical application will be apparent by reference to the following description in connection with the accompanying drawings, in which 100

Fig. 1 is a perspective view of a portion of a well drill rig to which my invention is applied.

Fig. 2 is an enlarged fragmentary elevational view of the front end of the walking beam, the multiplying parallel device being shown partly in section, and 105

Fig. 3 is a side elevational view of the front end of the walking beam showing the 110 multiplying parallel device swung out of functional position so that it will be out of

line with the pump rods to permit them to be pulled.

Referring now to the drawings, by numerals of reference

- 5 1 designates the band wheel which receives its motion from an appropriate prime mover (not shown) through the medium of the belt 2. The band wheel is carried on the crank shaft 3 supported by the jack posts 4,
- 10 the shaft 3 carrying the usual crank 5 connected to the pitman 6 which in turn is connected to the rear end 7 of the walking beam 8 mounted to swing on the Samson post 9.
- 15 All of the previously described mechanism is standard equipment. The stroke multiplying parallel motion is illustrated as comprising a truss beam consisting of two channels 10 and 11 connected in spaced relation by tie-bolts 12 and 13 so that they may be on opposite sides of the walking beam. The channels 10 and 11 when they are connected constitute the compression member of a truss, the tension members 14
- 20 and 15 being connected to a substantially U-shaped strut 16 which is adapted to straddle the front end of the walking beam 8, the strut serving also as a U-bolt or bracket which supports the truss upon the front end
- 25 of the walking beam through the medium of the bolt 17 which removably passes through the upper ends of the strut. The truss is also permanently fastened to the walking beam by the bolts 18 and 19 and the strap 20 held on the bolts by the nuts 21 and 22.

The truss constitutes an extension for the walking beam and at its front end on the bolt 13 is an elbow lever 23 pivoted at its angle upon the bolt 13. The toe of the horizontal leg 24 of the lever 23 is directed toward the front end or toe of the walking beam 8. The substantially vertical leg 25 of the elbow lever 23 is connected to compensating links or rods 26 and 27 by a bolt 28, the compensating links or rods 26 and 27 being anchored to the Samson post 9 by the anchor member 29 fastened to the Samson post by the clevis or yoke 30 which may be of any appropriate construction. The elbow lever may be braced by the braces 31 or the elbow lever consisting of the legs 24, 25 and braces 31 may be cast in a single piece in which event the legs would be braced by a web. The specific construction of the elbow lever is unimportant in the generic aspect of the invention for obviously it could be in the form of an angle plate if heavy enough metal was used. The forward end of the elbow lever is provided with a socket 32 to receive the T-shaped end 33 of the polish rod 34 connected to the pump rods in any appropriate manner.

It will be apparent that since the forward end of the bracket or truss extension is piv-

otally connected to the lever 23 at a point distant from the pivotal connection of the compensating means consisting of the rods 26 and 27 that as the lever 8 rocks, the pivot 28 will describe the arc indicated at 35, 70 while the pivot 13 will describe the arc indicated at 36 and that these arcs will intersect at approximately the point indicated at 37, therefore as the walking beam swings and the pivot 13 moves outwardly the pivot 75 28 will move inwardly a corresponding amount and vice versa, therefore the front end of the elbow lever will move in a substantially vertical line throughout the entire swing of the walking beam. 80

In actual practice there may be a slight deviation from a straight line but for all intentions and purposes the pull will be a direct perpendicular pull. In view of the fact that the power delivering element, that is the elbow lever is pivoted to the extended end of the truss and in view of the fact that it has a motion independent of the motion of the walking beam, it will follow that the stroke in addition to being in a straight 90 line will have a greater amplitude than if the pump rods were driven direct from the front or toe end of the walking beam. Consequently a longer stroke will be imparted to the working barrel of the pump on the 95 ends of the pump rods.

I have above intimated it is necessary to pull the pump rods periodically so in order to provide a convenient means for pulling them, the truss is pivoted to the bolt 12 by disconnecting the rods 26 and 27 and taking out the bolt 17 and the truss with its mechanism which it carries can swing down to the position shown in Fig. 3, while the walking beam has its front end directed upwardly, therefore the front end of the walking beam will be out of line with the rods so that they can be pulled in a convenient manner. 100

From the foregoing, it will be apparent 110 that the device constructed in accordance with the generic principles hereinbefore enumerated will give an increased stroke with a parallel motion so that the pump rods will not whip or crystallize as readily as they will under standard practice and in view of the fact that the stroke of the working barrel of the pump can be increased, that production must of necessity be increased with a slower motion than that usually practiced and that the device can be applied to a standard rig without in any way altering the rig. This feature alone is important due not to any inability of workmen to arrange or reconstruct the rig, but because of the inherent prejudice of oil operatives to change standard equipment with which they are familiar. 120

While this invention is primarily intended for use as a long stroke parallel motion 130

device for oil pumps, I comprehend that it is capable of other uses and I therefore do not wish to be limited to the specific application illustrated.

5. What I claim and desire to secure by Letters-Patent is:

1. In a stroke multiplying parallel motion device, a rocking beam, an elbow lever pivoted to one end of the beam at the angle 10 of the elbow lever and compensating means having one end anchored and the other pivoted to one arm of the elbow lever.

2. In a stroke multiplying parallel motion device, a rocking beam, an elbow lever pivoted to one end of the beam at the angle 15 of the elbow lever and compensating means having one end anchored and the other pivoted to one arm of the elbow lever, the pivots of the elbow lever describing intersecting arcs to maintain the end of the free 20 arm of the elbow lever in a straight line during the movement of the beam.

3. In a stroke multiplying parallel motion device, a rocking beam, a normally rigid 25 pivoted extension on the end of the beam, an elbow lever pivoted at the angle of the elbow lever to the extension, the elbow lever having a depending arm and compensating means anchored at one end, removably and 30 pivotally connected to the free end of the depending arm so that the compensating means may be detached from the arm and the pivoted extension may be swung down from the beam which supports it.

35. 4. In a stroke multiplying parallel motion device, the combination with a post, a beam pivoted on the post, an extension on the end of the beam, an elbow lever pivoted at its

angle to the extension, and compensating means pivotally anchored to the post and 40 pivotally connected to the free end of one arm of the elbow lever.

5. In a stroke multiplying parallel motion device, a rocking beam, an extension 45 pivotally secured to the rocking beam, means for fastening the extension rigid with the beam, an elbow lever pivoted at its angle to the extension and having one arm directed toward the free end of the beam and a compensating device anchored at one end and 50 removably connected to the free end of the other arm of the elbow lever.

6. In a stroke multiplying parallel motion device, a supporting member, means for attaching the supporting member to a rocking beam, an elbow lever pivoted at its angle 55 to the member, said elbow lever having a substantially horizontal arm and a substantially vertical arm, means on the horizontal arm for engaging a device to which power is to be applied and a compensating means having an anchor at one end and a pivoted connection at the other end with the free end of the vertical arm of the elbow lever.

7. In a stroke multiplying parallel motion device, a truss, means on one end of the truss for fastening the truss to a rocking beam, means intermediate the truss for engagement with the end of the beam, an elbow lever pivoted at its angle to the free end 70 of the truss, rods pivotally connected to the free end of one of the arms of the elbow lever and anchoring means at the other ends of the rods.

In testimony whereof I affix my signature.
EDWARD B. WINTERS.
